No. 797,327.

PATENTED AUG. 15, 1905.

P. L. SCHAAF.
FENCE POST MOLD.
APPLICATION FILED APR. 3, 1905.

UNITED STATES PATENT OFFICE.

PETER L. SCHAAF, OF BOTKINS, OHIO.

FENCE-POST MOLD.

No. 797,327.

Specification of Letters Patent.

Patented Aug. 15, 1905.

Application filed April 8, 1905. Serial No. 253,484.

To all whom it may concern:

Be it known that I, PETER L. SCHAAF, a citizen of the United States, residing at Botkins, in the county of Shelby and State of Ohio, have invented a new and useful Fence-Post Mold, of which the following is a specification.

This invention relates to fence-post molds, and has for its object to provide certain new and useful improvements whereby the mold can be conveniently assembled and set up in condition for use and also readily separated from the cast without danger of damaging the same. It is also proposed to enable the production of a series of openings transversely through a post for the reception of fence-wires and to properly support a wooden strip within the mold so as to be embedded in the cast for use in connecting fencing thereto.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a perspective view of a fence-post mold embodying the features of the present invention. Fig. 2 is a vertical longitudinal sectional view thereof, showing the mold filled and arranged to produce openings through the completed post. Fig. 3 is a similar view showing a wooden strip supported within the mold so as to be embedded in the face of the post. Fig. 4 is a cross-sectional view on the line 4-4 of Fig. 3. Fig. 5 is a similar view on the line 5-5 of Fig. 2. Fig. 6 is a sectional view illustrating the mold adjusted to produce wire-receiving openings in the post and to embed a wooden strip in one face of the post.

Like characters of reference designate corresponding parts in each and every figure of the drawings.

The present mold has been designed for producing cylindrical or slightly-tapered posts and is preferably formed of metal, including duplicate longitudinal semitubular sections 1 and 2, which are provided at their upper ends with complementary flared portions 3 and 4 to produce a filling-funnel. One longitudinal edge of each section is provided with a longitudinal groove or seat 5 and the other edge

is provided with an outwardly-offset flange or tongue 6, designed to fit within the groove or seat of the other molded section, so as to produce close joints between the sections to prevent escape of the material being molded.

For holding the mold-sections together when in use there is a series of bands 7 to embrace the sections below the funnel-top thereof, and these bands are connected by means of a series of connecting-bars 8, preferably three in number, located diametrically opposite one another and lying against the inner sides of the bands, so as to bear against the exterior of the mold. A suitable plate 9 is connected to the lower ends of the bars 8, so as to form a closure for the bottom of the mold.

Each mold-section is provided with a longitudinal series of perforations which are aligned with the perforations of the other section, and one of the sections is provided with a pair of set-screws 11, which pierce the section and are designed to support a wooden strip 12 within the mold and against the inner face of the adjacent section.

In using the mold it is set up, as shown in Fig. 1, with the funnel at the top. If it is desired to produce a series of diametric openings through the post for the reception of fence-wires, the mold-embracing clamp member is adjusted to locate the connecting-bars 8 at one side of the respective series of perforations 10, suitable rods or pins 13 being passed through the perforations. The mold is filled through the funnel at the upper end thereof and the material settles around the rods or pins 13, which are of course withdrawn when the post has become set, thereby producing diametric openings through the post. When the post has set sufficiently to stand of itself, the mold is inverted and placed upon its funnel end, after which the clamping device is drawn off from the small end of the mold, and the mold-sections are then separated sidewise from the cast, thereby leaving the post standing upon its broad base, which was produced by the funnel portion of the mold. The pins or rods 13 may be removed before or after inverting the mold, as may be desired.

When it is desired to have a wooden strip embedded in one face of the post for the attachment of fencing thereto, the strip 12 is placed in the mold preparatory to filling the same, and the set-screws 11 are set into the strip, so as to prevent displacement thereof during the filling of the mold. The strip is

of course drawn up snugly against the inner wall of the mold by the set-screws 11 in order that the outer face of the strip may be exposed at the outer face of the post, so as to receive the fastenings to be employed for securing fencing to the post.

When the wooden strip is employed and it is not desired to have the openings which are produced by the pins or lugs 13, the perforations 10 are closed by adjusting the bars 8 to lie across said perforations. In some instances it may be desirable to produce openings through the post and also employ the wooden strip 12, in which event the mold is adjusted, as shown in Fig. 6, so as to bring one of the bars 8 between the perforations 10 and the set-screws 11, whereby the perforations 10 are free to receive the pins or bars 13, and the wooden strip 12 is supported at one side of the series of openings to be produced by the pins 13. When it is desired to omit the enlarged base, the mold is filled up to a point short of the funnel portion, thereby producing a shorter post, which is adapted to be set upon a separate base.

Having fully described the invention, what is claimed is—

1. A fence-post mold comprising separable longitudinal sections, and connecting means for the sections consisting of a series of clamping-bands to embrace the sections and connecting-bars extending throughout the series of bands, whereby the clamping means is applicable and removable as a whole at one end of the mold.

2. A fence-post mold comprising separable longitudinal sections, a series of clamping-bands removably embracing the mold - sections, connecting-bars extending between the series of bands, and a closure-plate for one end of the mold, said plate being connected to the bars for simultaneous application and removal therewith.

3. A fence-post mold provided in diametrically opposite sides with corresponding perforations, and means carried by the mold and adjustable thereon to cover and uncover the perforations.

4. A fence-post mold provided in diametrically opposite portions with corresponding perforations, bands rotatably adjustable upon the mold, and bars connecting the bands and adjustable therewith to cover and uncover the perforations.

5. A fence-post mold comprising separable sections provided with diametrically opposite corresponding perforations, clamping means removably embracing the sections to connect the same and capable of adjustment to cover and uncover the perforations.

6. A fence-post mold comprising separable sections provided with diametrically opposite corresponding perforations, clamping-bands removably embracing the sections and rotatably adjustable thereon, and bars connecting the bands and movable therewith to cover and uncover the perforations.

7. A fence - post mold which is closed throughout its periphery and open at one end for filling, diametrically opposite portions of the mold being provided with longitudinal series of corresponding perforations, means piercing the mold between the series of perforations to support a strip within the mold to be embedded in the cast, clamping-bands rotatably adjustable upon the mold, and bars connecting the bands and movable therewith to cover and uncover the perforations.

In testimony that I claim the foregoing as my own I have hereto affixed my signature in the presence of two witnesses.

PETER L. SCHAAF.
